UNITED STATES PATENT OFFICE.

FRED FORREST BERRY, OF LOS ANGELES, CALIFORNIA.

FOX KENNEL.

Application filed October 21, 1926. Serial No. 143,149.

This invention relates to a kennel for animals which are intolerant of human contact with the kennel, and pertains more particularly to a kennel which has a compartment disposed within a shell, which compartment may be inspected without necessitating contact of the inspector.

Fox kennels are arranged with a compartment jacketed by an outer shell to provide an entrance to the compartment approached by a tortuous passage and sheltered from drafts and light. Such kennels are desirable for reasons well known to fox breeders.

Fox, especially silver fox whose hides and furs are very valuable, are especially intolerant of human interference with their young. Many will remove their young from a kennel which has been contaminated by human touch after the birth of the young. The mother in many instances will kill the young or remove them to other places upon determining that the kennel has been touched by a human. Removal by the mother subjects the young to vicissitudes from which the young often die. In many instances the mother is unable to nurse her young, in which case it becomes advisable to save the life of the litter to transfer the young so as to be attended by other animals such as cats. The saving of life is a valuable asset to the fox breeder. Inspection for this reason and for other reasons becomes advisable in the early life of the young. The present invention has for its primary object the provision of a kennel which may be opened, inspected and closed without contaminating the bed or nest compartment with human contact. Some means to warm the kennel is also advisable. The present invention contemplates a structure whereby an electrical heating device may be employed for the purpose of keeping the kennel warm.

These objects together with other objects and corresponding accomplishments may be obtained by means of the embodiment of my invention illustrated in the accompanying drawing, in which:

Fig. 1 is a perspective view of a kennel closed and ready for occupancy; Fig. 2 is a vertical sectional view through the kennel showing the cover of the outer shell open and also the lid of the inner or bed compartment open; Fig. 3 is a section as seen on the line 3-3 of Fig. 2; and Fig. 4 is a

plan view partly in section showing the kennel opened for inspection.

The outer shell of the kennel is of box form and includes three stationary walls indicated by 5, 6, and 7. There is a bottom 8 and a roof 9 which is hinged so that it may be opened as shown in Fig. 2. The roof is arranged to be sloping so as to shed water. A door 10 is hinged to the wall 5 completing the outer shell. A suitable hook and eye indicated by 11 or any other convenient means may be provided for holding the door 10 closed.

Disposed within the shell is a second door 12. This door cooperates with a casing 13 within the shell and is so disposed that when closed, it is close to the door 10. Mounted on the inner side of the door 12 is a bed compartment or chamber 14. This compartment is closed on all sides except the top for which a lid 15 is provided, this lid being hinged. There is a double bottom to provide a space 17 at the lower part of the compartment.

The entrance to the shell is through an opening 18 in the side 7, and the entrance to the compartment is through an opening 19. The animal enters through opening 18 and along the passageway between the wall 6 and the compartment, then through the passageway between the wall 5 and the compartment and into the compartment opening 19. Normally the kennel is in the condition shown in Fig. 1, the door 10 being closed over the door 12. If it is desired to inspect the young, this is done during the absence of the mother. Door 10 is swung open to the position shown in Fig. 4, exposing the face of door 12. The latter is then swung outwardly as shown in Fig. 4, to bring the inner compartment out of the shell in a position where the interior of the compartment may be viewed through the opening 19. Thus, the inside of the kennel need not be touched by the inspector. The method of closing the kennel is obvious. There will be no odor or contamination of the kennel apparent to the mother.

It is advantageous to supply heat to the young by warming the kennel. To this end, I have provided an opening 20 in the rear wall of the bottom chamber 17 and a corresponding registering opening 21 in the door 12. Mounted upon the door 10 so as to be disposed within the chamber 17, when doors 10 and 12 are closed, is an electric

heater 22. This may be of any suitable type such as a resistance heater, sufficient to supply heat to the kennel and keep it comfortable. The conductors 23 for the supply of energy, extend along the rear of the door to the wall 5 and are connected to a suitable source of supply of electrical energy. These conductors are flexible and will act as a hinge as door 10 is opened and closed.

10. The nest compartment may be cleaned by opening the lid 15. However, some means must be provided to lock the lid closed to avoid accidental pinching of the tails of the young and injury to the fur which may occur 15 when the young play or fight. To this end, a board or plate 24 is fastened to the cover so as to rest thereon when the cover is closed. The mother has a desire to remove the young from the nest compartment and tries 20 to hide them. The space between lid 15 and cover 9 offers a hiding place. If permitted to place her young there, danger will be encountered, due to the opportunity for the young to fall to the floor of the kennel, 25 break their legs and otherwise injure themselves. The board 24 is arranged to serve as an end closure for this space. Thus, it serves two functions, one to close the space above the lid 15 and the other to lock the lid closed.

It is obvious that I have provided a kennel structure such that the compartment housing the young may be moved to position so that the interior may be viewed 30 without human contact with the interior. The kennel is also of such a character as to appeal to the mother of the young in the matter of secrecy, there being a tortuous corridor for passing in and out. There is also convenient means for heating. The structure is economical to construct, strong and efficient.

It is obvious that a plurality of nests may be placed within a single shell, there being 45 separate doors for each compartment. A single entrance may be provided and a partition wall dividing the shell into two chambers. A hole for intercommunication may be formed in the partition. However, this is mere duplication.

What I claim is:

1. In a kennel, the combination of a shell having a door in one of its walls, and a bed compartment or nest box secured to the door so as to be swung out of said shell with the opening of said door.

2. In a kennel, the combination of a shell having in one of its walls an outer and an inner door, the outer door overlying the inner door, a bed compartment or nest box secured to the inner face of the inner door, so as to be swung out of said shell with the opening of said inner door.

3. In a kennel, the combination of a shell 60 having a door in one of its walls and a bed

compartment or nest box secured to the door so as to be swung out of said shell with the opening of said door, said bed compartment being spaced from the wall of the said shell so as to provide an L shape corridor, there being an opening in said compartment at the inner end of said corridor and an opening in said shell at the outer end of said corridor.

4. In a kennel, the combination of a shell 70 having in one of its walls an outer door and an inner door, the outer door overlying the inner door, a bed compartment or nest box secured to the inner face of the inner door so as to be swung out of said shell with the opening of said door, said bed compartment being spaced from the wall of said shell so as to provide an L shape corridor, there being an opening to said compartment at the inner end of said corridor and an opening 80 in said shell at the outer end of said corridor.

5. In a kennel, the combination of a shell 90 having a door in one of its walls and a bed compartment or nest box secured to the door so as to be swung out of said shell with the opening of said door, and a heater disposed within said kennel.

6. In a kennel, the combination of a shell 95 having in one of its walls, an outer and an inner door, the outer door overlying the inner door, a bed compartment or nest box secured to the inner face of the inner door so as to be swung out of said shell with the opening of said inner door said compartment being spaced from the wall of said shell so as to provide an L shape corridor, there being an opening in said compartment at the inner end of said corridor, and an opening in said shell at the outer end of said 100 corridor, there being a hinged lid for said compartment.

7. In a kennel, the combination of a shell 105 having a door in one of its walls and a bed compartment or nest box secured to the door so as to be swung out of said shell with the opening of said door, said compartment having a hinged lid.

8. In a kennel, the combination of a shell 115 having in one of its walls, an outer door and an inner door, the outer door overlying the inner door, bed compartment or nest box being secured to the inner face of the inner door so as to be swung out of said shell with the opening of said door, the outer shell 120 having a hinged cover and the compartment having a hinged lid.

9. In a kennel, the combination of a shell 125 having in one of its walls an outer door and an inner door, the outer door overlying the inner door, a bed compartment secured to the inner face of the inner door so as to be swung out of the said shell with the opening of said door, said bed compartment or nest box being spaced from the wall so as 130

to provide an L shape corridor, there being an opening in said corridor at the inner end thereof and an opening in said shell at the outer end of said corridor, the shell having a hinged cover and said compartment having a hinged lid.

10. In a kennel, the combination of a shell having a door in one of its walls, a bed compartment or nest box secured to the door so as to be swung out of said shell with the

opening of said door, there being a closed chamber at the bottom of said compartment and a heater mounted on said door so as to be disposed within said chamber when said door is closed.

In witness that I claim the foregoing I have hereunto subscribed my name this 27th day of September, 1926.

FRED FORREST BERRY.
